TILTING MECHANISM FOR VENETIAN
BLINDSStanley E. Campbell, Saginaw, Mich., assignor to
Germain Manufacturing Company, Saginaw,
Mich., a corporation of Michigan

Application May 18, 1935, Serial No. 22,137

6 Claims. (Cl. 156—17)

This invention relates to Venetian window blinds. It pertains more particularly to improvements in the mechanism by which the tilt rail is tilted to open or close such blinds.

5 Tilting devices of such character are arranged to actuate the tilting rail at an end thereof. The tilting mechanism is usually mounted in a housing which is fixed to the head rail or to some part of the window, and is operated by pulling a cable that hangs down alongside the blind. By the term "cable" is meant any flexible cord, chain or the like.

The objects attained by my present improvement, as to its general aspects, are: compactness 15 of the actuating mechanism; no parts projecting from the housing, except the spindle for the tilt rail; adaptability for use on blinds with wider or narrower head rails and tilt rails; and adaptability to either the right-hand or left-hand side 20 of a window frame; positive locking.

In respect to its mechanical operation, the advantageous results attained by my invention are: to provide an operating mechanism that will give a smooth, even rotating or tilting movement to the tilt rail of a Venetian blind, without any undesirable noise in the tilting device itself and without vibration effects being transmitted, as noise or clatter, from the window frame through the frame of the building, so as to be audible in adjoining rooms; to provide an actuating mechanism in which the pull on the cord shall be easy and virtually uniform, irrespective of the angle to which the tilt rail and slats may be inclined, that is to say, without any appreciable changes in pull resistance due to changing angularity of the moving parts, which heretofore has been an undesirable feature of tilting devices wherein arms and links were employed that produced a variable eccentric thrust at different degrees of tilting; to provide a screw-actuated tilting device wherein a given distance of cord pull shall completely tilt the slats from open to closed position with a relatively great number of turns of the screw, as compared with former structures in which the length of cord movement produced only a few turns of the screw, the advantage being that the cord wheel can now be made unusually small and can be concealed in a compact housing, yet will exert 45 adequate tilting force with very light pull on the cord; to provide a simplified and easily detachable means for keeping the cord on the wheel; and a simple and inexpensive means for maintaining in the screw any desired amount of frictional resistance against turning and for taking

up wear and avoiding back lash; and to provide a housing construction that is inexpensive to manufacture, gives ready accessibility to the working parts and enables them to be rapidly and accurately assembled.

With the foregoing and certain other objects in view, which will appear later in the specifications, my invention comprises the devices described and claimed and the equivalents thereof.

In the drawing Fig. 1 is a front view of the 10 tilting mechanism as it appears with the front wall of the housing removed.

Fig. 2 is a top plan view of the housing and its associated mechanism.

Fig. 3 is a side view of the housing with one of 15 its sides removed and showing its application to wider or narrower tilt rails of a window frame.

Fig. 4 is a perspective view of the spring device for keeping the cord in place on a screw-actuated 20 wheel,

Fig. 5 is a perspective view of the housing as it appears with the interior tilting mechanism removed.

In the preferred form of the device which is chosen for purpose of illustration, numeral 1 designates a conventional tiltable top rail of a Venetian blind. The housing, which is preferably made of sheet metal, comprises a front wall 2 and side walls 3, 4 formed with outwardly projecting flanges 5 adapted to be fastened to the head rail 6 of the Venetian blind by means of screws or otherwise. The operating mechanism is enclosed within the housing and consists of a wheel 7 grooved to take a cable or a cord 7a. The wheel is fixed to a threaded bolt or screw 8, 35 the threads being shown diagrammatically in Fig. 3. These threads are of relatively fine pitch, that is, a pitch which is standard for machine bolts of corresponding size. The threads may be of usual V-shape, or square. The screw 8 is supported by and rotates on an end bearing 10 secured to the front wall of the housing and a bearing 11 mounted in a fixed support at the rear end of the housing. These bearings are preferably in the form of conical or ball tipped screws 45 received in recesses in the ends of the bolt 8. Preferably the bearing 11 is a set screw threaded through a bracket 12 so as to be capable of endwise adjustment for the purpose of producing an adjustable amount of endwise thrust against bolt 8 and thereby produce any desired amount of frictional resistance against turning the bolt when the cord 7a is pulled. The end bearing 11 may be locked in any adjusted position by means of a set nut 13. The bearing 10 may be secured 50

to the front wall 2 of the housing by riveting, as shown, or by any other suitable means.

The bracket 12, which may be formed of sheet metal, serves as a support for the adjustable bearing 11, and is connected to the side walls of the housing 3, 4, preferably by spot welding, as is indicated in Fig. 2.

Bracket 12 is formed with one or more inwardly projecting guide flanges 14, as shown in Fig. 2.

10 An internally threaded rider 9 is mounted on the bolt 8, being prevented from turning by the guides 14 during its travel along the bolt when the latter is rotated. The rider 9 may be made in the form of an elongated nut, or it may be formed of pressed metal. On the bottom face of the rider is a toothed rack 15 which engages a pinion 16. The pinion is mounted on a spindle 17 by means of the dowel pin 16a. The spindle 17 is rotatable in bearings 18 on the housing walls 3, 4. An end of the spindle projects beyond the wall of the housing and is received in a hole bored axially in the tilttable top rail 1. A clutch device 19 is fixed to the spindle 17, its prongs being likewise received in the rail 1 so that rotating the spindle 17 will tilt the rail about its axis, as is indicated by the dotted lines in Fig. 1.

30 To keep the cord 7a normally in the groove of the wheel 1 I prefer to employ the spring device illustrated in Fig. 4, consisting of a piece of flat spring or ribbon metal shaped so as to present at its middle portion 20 a bearing face to yieldingly contact with the cord and having laterally looped side members 21 to give a proper degree of resilience and to insure proper contact of the bearing portion 20 upon the cord, even though the latter become worn or stretched. The free ends 22 project outwardly in opposite directions and can be releasably secured to the side walls 3, 4 of the housing. Preferably, openings 23 are 40 provided in the housing, and the ends 22 are easily insertable in the openings by squeezing the ends of the spring together and allowing them to enter the openings 23 by springing outwardly, as shown in Fig. 1.

45 In Fig. 3 the tilting mechanism and housing are shown as applied to the head rail 6 of a window frame, the front wall of the housing being flush with the edge of the rail.

50 The spindle 17 is positioned on the housing so that the front edges of the blind slats shall be located properly with respect to the window frame when the blinds are open. For exceptionally large windows wider blind slats are used, and in such circumstances the axis of the tilttable top rail 1, and of spindle 17, will be located with respect to the housing so that the front edges of the wider slats when opened will be correctly aligned with the edge of the head rail 6 of the window frame. Such different position of the shaft 17 is indicated by dotted lines at 24 in Fig. 5.

55 Obviously, the only change necessary to make in the housing in order to accommodate either narrow or wide blind slats is to shift the location of the bearings for spindle 17, and it is apparent that no other change need be made in the tilting mechanism because the operation of the rider 9 and its rack 15 will not be altered by such change. This arrangement is of advantage in the production of tilting devices for various sized windows, because one size of housing will answer all requirements.

70 In Fig. 3, W indicates the head rail 6 of a large window, and w, that of a smaller window.

75 In operation, cord 7a is pulled to turn the wheel 1 and move the rider 9 in the appropriate direc-

tion lengthwise of bolt 8. The pinion 16, driven by rack 15, turns the shaft 17 and the clutch members 19. The small pitch of screw 8, say thirteen threads per inch for a one-half inch diameter bolt, enables a light pull on cord 7a to move the rider 9 easily but positively through the required distance to produce the desired tilt of rail 1; it also enables wheel 1 to be made unusually small in diameter, thus minimizing the width of the housing. A steady frictional resistance of any 10 desired amount, counted to the pull on cord 7a, may be produced by adjusting the bearing screw 11, thus taking up all undesirable back lash in the mounting of bolt 8 and compensating for wear.

15 The pinion 16 and rack 15 are of fine pitch, preferably about thirty-two, hence there is possible only a negligible amount of play between the rack and the pinion. During the rotation of bolt 8 the guides 14 keep the rider 9 from rotating, and also keep the rack and pinion properly aligned with each other.

20 The tilting movement throughout its entire range is smooth and even, the pull on the cord 1 is light and uniform, without jerks or uncertainty, and noiseless, with no undesirable vibrations 25 transmitted to the window frame.

25 After the cord has been placed in the grooves of wheel 1 the removable keeper, Fig. 4, can be snapped in place easily and quickly to hold the cord in position, regardless of wear on the cord 30 or unevenness in its diameter.

35 While I have shown and described the member 1 as being the conventional top tilttable rail of a Venetian blind, it will be understood that the terms "tilt rail" or "tiltable rail" as employed in the foregoing description are intended to include any equivalent tilttable member, such as a tilttable roller or spool constructed and operating in the manner of the conventional form shown.

40 Having thus described my invention, what I claim and desire to secure by Letters Patent is:

1. Means for tilting the rail of a Venetian blind, comprising a stationary housing and a cable-actuated threaded bolt, cable retaining means, bearings on said housing so constructed and arranged as to support said bolt for axial rotation, a screw on the housing adapted to create variable amounts of lengthwise pressure of said bearings against said bolt in such a manner as to frictionally regulate the resistance of the 50 bolt to such cable actuation, a threaded rider on said bolt, a guide member carried by the housing and constraining said rider against undue rotation, a rack on said rider extending lengthwise of said bolt, a pinion meshing with 55 said rack, a spindle for said pinion projecting beyond a side wall of the housing, spindle bearings in the housing, and a clutch device on the spindle engaging said rail.

2. In an actuating mechanism for the tilttable 60 rail of a Venetian blind including a cable-actuated rotatably mounted threaded bolt, an adjustable end bearing for said bolt, a rider threaded on said bolt to travel lengthwise thereon, and guiding means engaging the rider in a manner 65 to prevent undue rotation thereof, in combination, a toothed rack on said rider, and means operatively connecting said rack to an end of said tilttable rail.

3. In an actuating mechanism for the tilttable 70 rail of a Venetian blind including a cable-actuated rotatably mounted threaded bolt, a rider threaded on said bolt so as to travel lengthwise thereon, and guiding means engaging the rider and adapted to prevent undue rotation thereof, 75

in combination, a rack on said rider extending lengthwise thereof, and means operatively connecting said rack to an end of said tilttable rail, said connecting means being arranged and adapted to support an end of the rail and to impart tilting movements thereto.

4. Actuating means for the tilttable rail of a Venetian blind including a housing, a cable-actuated rotatable threaded bolt and bearings on said housing supporting said bolt for axial rotation, in combination, frictional adjusting means adapted to regulate the resistance of said bolt counter to forces exerted by the cable and tending to rotate the bolt, said means comprising a threaded screw arranged and operative to vary the lengthwise pressure of said bearings against the bolt.

5. In mechanism for actuating the tilttable rail

of a Venetian blind having a housing containing a cable-actuated threaded rotatable bolt carrying a rider, in combination tapered center bearing members on said housing supporting said bolt for axial rotation, one of said bearing members being threaded in said housing and arranged for endwise adjustment in a manner to impart to the bolt frictional resistance counter to pulling efforts exerted on the cord tending to rotate the bolt, and means for fixing said counter bearing members in various adjusted positions.

6. A structure as set forth in claim 3 wherein the means operatively connecting the rack to an end of a tilttable rail comprises a pinion meshing with said rack and mounted on a rotatable shaft supported in bearings on the housing.
